No. 728,952.

PATENTED MAY 26, 1903.

C. B. MILLER & O. D. COTTON.
MEANS FOR STOKING FURNACES.

APPLICATION FILED MAY 19, 1902.

NO MODEL.

UNITED STATES PATENT OFFICE.

CHARLES B. MILLER, OF CHICAGO, ILLINOIS, AND ORVILLE D. COTTON, OF DETROIT, MICHIGAN; SAID MILLER ASSIGNOR TO SAID COTTON.

MEANS FOR STOKING FURNACES.

SPECIFICATION forming part of Letters Patent No. 728,952, dated May 26, 1903.

Application filed May 19, 1902. Serial No. 107,909. (No model.)

To all whom it may concern:

Be it known that we, CHARLES B. MILLER, residing at Chicago, in the county of Cook and State of Illinois, and ORVILLE D. COTTON, residing at Detroit, in the county of Wayne and State of Michigan, citizens of the United States, have invented certain new and useful Improvements in Means for Stoking Furnaces, of which the following is a full, clear, and exact specification.

Our invention relates to that class of furnace-stokers in which the fuel is fed into the furnace by a number of pushers or plungers which move back and forth adjacent to the mouth of a fuel-hopper, and thereby push the fuel onto the grate.

One of the objects of our invention is to provide improved means for causing the pushers to feed more or less profusely at one point than at another, so as to compensate for the difference in degree of burning power at different points in the furnace, and thereby maintain a uniform fire throughout the grate-surface. In furnaces of this character the stoker is operated by an outside reciprocating bar, which is run continually for other purposes as well, it being detached from the stoker mechanism when it is not desired to operate the latter.

A further object of our invention is to provide improved means whereby this disconnection may be readily effected without endangering any parts by the continual motion of the operating-bar.

With these ends in view our invention consists in certain features of novelty in the construction, combination, and arrangement of parts by which the said objects and certain other objects hereinafter appearing are attained, all as fully described with reference to the accompanying drawings and more particularly pointed out in the claims.

In the said drawings, Figure 1 is a detail transverse sectional view on the line 1 1, Fig. 3, of one of the stoker pushers or plungers, its operating mechanism, and a part of the hopper. Fig. 2 is an enlarged perspective view of one end of one of the pushers or plungers upside down, one end being cut off. Fig. 3 is a longitudinal sectional view on the line 3 3, Fig. 1. Fig. 4 is a front elevation of the

outside of the furnace, showing the stoker-operating bar and connected mechanism. Fig. 5 is a plan section taken on the line 5 5, Fig. 4; and Fig. 6 is a vertical section on the line 6 6, Fig. 4.

1 is a part of a fuel-hopper, which may be of the usual or any suitable construction and which in furnaces of this character is usually arranged at one side of the grate-bars, which are indicated in Fig. 1 by the dotted line 2 and which lead downwardly from a shelf 4, over which the hopper 1 is arranged, and upon which shelf slide the similarly-constructed stoker plungers or pushers 5 6, the latter being interchangeable and interposed between the shelf and the mouth of the hopper, so that as they move toward the inner edge of the shelf the fuel resting thereon will be pushed off onto the grate-bars.

Any desired number of the plungers or pushers 5 6 may be employed. For the purposes of this application for patent two are shown, and each is preferably in form of an inverted box having the under side of its top portion provided with a pair of depending lugs 7, formed at each end thereof, and the shelf 4 is provided with a slot 8, upwardly through which project rocker-arms 9 10, two of these arms being preferably employed for each of the pushers or plungers and one engaging between the lugs 7 of each pair, as shown in Fig. 3, so that as the arms oscillate the pushers or plungers will be moved back and forth under the mouth of the hopper 1 a distance proportioned to the lengths of the arms. The arms are secured to a rock-shaft 11, which is common to all of them; but, as shown in Fig. 3, the arms which engage with the depending lugs of one of the pushers or plungers 5 6 are shorter than the others, so that, although secured to the same shaft, the shorter arms will produce less movement of the pusher 6 than is produced by the longer arms on the pusher 5, and consequently one pusher will feed more fuel than the other one.

The upper ends of the arms 9 10 may be provided with antifriction-rollers 12, capable of being inserted between the lugs 7. This construction affords an inexpensive and at the same time highly efficient and durable means for giving the pushers different degrees of

throw or movement, and it also provides for making all of the pushers of uniform construction, rendering it immaterial whether they are to be used for the long stroke or the 5 short stroke, this being entirely determined by the length of the arms 9 10.

The outer end of the shaft 11 is provided with a crank-arm 13, whose lower end carries a wrist 14, which engages in a notch 15, formed 10 in a lug 16, attached to a bar 17, which is the aforesaid reciprocating bar employed in furnaces of this character for imparting motion to the stoker mechanism and at the same time operating other parts, such as the clinker-bar 15 of the grate, &c. (Not necessary to illustrate.) This lug 16 is supported on the top of the bar 17 and secured in place by hinges 18 in such a manner that when desired the lug 16 may be turned downwardly and outwardly 20 in the manner shown in dotted lines in Fig. 6, so as to escape the wrist 14 and allow the stoker mechanism to remain at rest. When it is desired to continue the operation of the stoker mechanism, the lug 16 is again turned 25 upwardly in the position shown in Figs. 4 and 5; but in order that its end may not strike the wrist 14 when thus turned upwardly through carelessness, and thereby injure some of the parts, the inner face of the lug 16 at each end 30 or on both sides of the notch 15 is beveled or attenuated toward the outer ends, as shown at 19, so that the bevel will strike the wrist and again throw the lug outwardly and downwardly, thereby avoiding any clash and break- 35 age. The outer side of the lug 16 is provided with a stop or support 20, which comes against the face of the bar 17 and holds the lug in a horizontal position.

If desired, the face of crank-arm 13 may be 40 provided with a loop or socket 21 for the insertion of a hand operating-lever, (not shown,) usually employed when it is desired to work the stoker by hand.

Having thus described our invention, what 45 we claim as new therein, and desire to secure by Letters Patent, is—

1. A furnace comprising a fuel-hopper, a shelf having slots and located beneath the fuel-hopper, a plurality of similarly-constructed 50 interchangeable plungers loosely mounted on the shelf over the slots of the lat-

ter, each having depending paired lugs and a rock-shaft mounted beneath the shelf and having upwardly-extending arms projecting through the slots and working between the depending paired lugs for reciprocating the plungers. 5

2. A furnace comprising a fuel-hopper, a shelf having slots and located beneath the fuel-hopper, a plurality of similarly-constructed interchangeable plungers loosely mounted on the shelf over the slots of the latter, each having depending paired lugs and a rock-shaft mounted beneath the shelf and having upwardly-extending arms of different 6 lengths projecting through the slots and working between the depending paired lugs for reciprocating the plungers different distances. 6

3. A furnace comprising a fuel-hopper, a shelf having slots a plurality of plungers each 7 having depending paired lugs located above the slots in the shelf, a rock-shaft, mounted beneath the shelf and having upwardly-extending arms projecting through the slots and between the depending paired lugs for reciprocating the plungers, a pendent crank-arm having a wrist and fixed to the rock-shaft, and a reciprocating bar having a surmounting lug formed with a notch receiving the wrist. 7

4. A furnace comprising a stoking device 8 having a shaft provided with a crank-arm carrying a wrist, and a reciprocating bar having a hinged lug formed with a notch receiving the wrist. 8

5. A furnace comprising a stoking device 8 having a shaft provided with a crank-arm carrying a wrist and a reciprocating bar having a hinged lug formed with a notch receiving the wrist and bevels, on the inner side of the lug, extending in opposite directions. 9

6. A furnace comprising a stoking device having a shaft provided with a crank-arm carrying a wrist, and a reciprocating bar having a hinged lug formed with a notch receiving the wrist and a stop to limit the movement of 9 the lug. 9
